UNITED STATES PATENT OFFICE.

JOHN S. McDANIEL, OF WILMINGTON, DELAWARE, ASSIGNOR OF ONE-HALF
TO JAMES WATSON, OF PHILADELPHIA, PENNSYLVANIA.

CONDENSER-HEAD.

SPECIFICATION forming part of Letters Patent No. 243,285, dated June 21, 1881.

Application filed April 15, 1881. (No model.)

To all whom it may concern:

Be it known that I, JOHN S. McDANIEL, a citizen of the United States, residing at Wilmington, in the county of New Castle, State of Delaware, have invented a new and useful Improvement in Condenser-Heads for Exhaust-Steam Pipes, which improvement is fully set forth in the following specification and accompanying drawings, in which—

10 Figure 1 is a top or plan view of the condenser-head embodying my invention. Fig. 2 is a central vertical section in line x x , Fig. 1.

Similar letters of reference indicate corresponding parts in the two figures.

15 My invention consists of a head for an exhaust-steam pipe formed of a shell provided with deflectors and openings adjacent thereto, whereby the water of condensation may be directed to a surrounding jacket, from whence it may be discharged or collected.

It also consists of a guard for preventing return of the water to the exhaust-pipe.

It further consists of a guard for preventing the water in the jacket from splashing by ebullition through the top of the head.

20 Referring to the drawings, A represents a hollow body or shell which is adapted to be attached to a pipe, B, for exhaust-steam from any source, said shell being preferably of conical form, the widest portion being above.

Within the shell are secured opened and closed deflectors C C' D D', which are arranged alternately one above the other, and in the wall of the shell are openings a , which are adjacent to the place of connection of the open deflectors with the wall, said openings communicating with a jacket, E, which surrounds the shell. The deflectors are dishing upwardly, so that their highest points are at the center, 25 and the top A' of the shell is also dishing and open at its center.

At the base of the shell is secured an upright pipe, F, surrounding which at the extreme lower end is a series of openings, b , 30 which communicate with the jacket E, the bottom of the latter being closed excepting at the place of connection of the discharge-pipe G.

H represents a guard which is secured to and projects from the exterior of the shell A,

near the upper end thereof, so as to partly close the space of the jacket E, the top of the latter being covered by a perforated plate, c .

The operation is as follows: When the exhaust-steam enters the shell A from the pipe B it is directed through the center of the open deflector C against the closed deflector D, then around the circumference of the latter against the solid portion of the deflector C', and thence to the center of said deflector. It next strikes the center of the deflector D', and finally reaches the top A', whereby it has been well disintegrated or broken, the remnant, inert or having little power, escaping through the central opening, d , or side openings, a' b' , to the atmosphere where the resultant water of condensation is so small as to be scarcely perceptible. The water of condensation within the shell drops on the ledges C C' and rolls down the side of the shell and reaches the openings a , through which it passes into the jacket E, from whence it is discharged through the pipe G, and may thereby be gathered and utilized. Should any steam condense on the under side of the lower deflector, C, the water runs down the side of the shell A, and entering the bottom openings, b , passes into the jacket E, the guard F preventing the return of the water to the exhaust-pipe. Should there be violent ebullition or spurting of water in the jacket E the same is checked upwardly by the guard H, and the water is thus prevented splashing outside of the head.

25 The discharge-pipe G is of L form, the bottom of the vertical portion having a closing cap, G', which, when removed, permits sediment, &c., to be discharged from the jacket and the discharge-pipe.

The wall of the jacket E, being exposed to the cooling effects of the atmosphere, assists in causing the condensation of the steam.

Having thus described my invention, what I claim as new, and desire to secure by Letters Patent, is—

30 1. In a condenser, a series of alternating open and closed deflectors, a shell surrounding the same, an exterior jacket and a discharge-pipe at the bottom of the space between the shell and jacket, the said shell being pro-

vided with outlets which communicate with said space, substantially as set forth.

2. The condenser-shell A and exterior jacket, E, in combination with the guard H, which only partially closes the space between the two, in order to allow the water of condensation to run down below said guard while preventing water from rising above it while in ebullition.

10 3. The alternating open and closed deflectors, shell, jacket, and guard H, which partly closes the space between the guard and jacket, in combination with bottom guard, F, which prevents the water of condensation from running back down the inlet-pipe, substantially as set forth.

4. A series of alternating open and closed deflectors, in combination with a shell which touches the edges of the open deflectors, and which is provided with openings immediately 20 above the same, to allow the water of condensation to run from said deflectors into a space external to said shell, substantially as set forth.

5. In combination with the deflectors and jacket E, the shell A and plate c, having, respectively, holes a' and b' for the outlet of steam, substantially as set forth.

JOHN S. McDANIEL.
